SHUTTER FOR ACCORDIONS

Salvatore Rabuazzo, New York, N. Y.

Application February 6, 1936, Serial No. 62,617

7 Claims. (Cl. 84—376)

This invention relates to accordions. It is particularly directed to control mechanism for the shutter valves for accordions and the like instruments.

5 An object of this invention is to provide in an accordion having a highly improved shutter valve control mechanism so constructed that the same may be actuated easily by the player while his hand is at any position on the key board.

10 A further object of this invention is to provide a highly simplified and positive shutter control for accordions of the character described.

A still further object of this invention is to provide in an accordion of the character described, means to indicate the relative position of the shutter valves.

Yet another object of this invention is to provide a neat and compact shutter control mechanism which shall be relatively inexpensive to manufacture, which may be readily incorporated into accordions and which shall yet be practical and efficient to a high degree in use.

Other objects of this invention will in part be obvious and in part hereinafter pointed out.

25 This invention accordingly consists in the features of construction, combinations of elements, and arrangement of parts which will be exemplified in the construction hereinafter described, and of which the scope of application will be indicated 30 in the following claims.

In the accompanying drawings, in which is shown one of the various possible illustrative embodiments of this invention,

Fig. 1 is a top end view of an accordion embodying the invention, showing the indicating device;

Fig. 2 is a cross-sectional view taken on line 2—2 of Fig. 1 with parts broken away;

Fig. 3 is a cross-sectional view taken on line 40 3—3 of Fig. 2;

Fig. 4 is a cross-sectional view taken on line 4—4 of Fig. 1;

Fig. 5 is a partial front elevational view of the shutter cover plate with parts broken away to 45 show the interior construction;

Fig. 6 is a partial, perspective view of the slide valves and actuating levers;

Fig. 7 is an enlarged, detailed view of the indicating mechanism;

50 Fig. 8 is a plan view of the indicating dial; and

Fig. 9 is a front view of a modified form of gear wheel.

Referring now in detail to the drawings, 10 designates one end of an accordion embodying 55 the invention. The same comprises a housing or

box-like frame 11 for one end of the accordion to which the bellows is attached in any suitable manner. The housing 11 comprises side walls 12 and 13 and top wall 14. The housing 11 contains the wind cells 16, slidably supporting the shutter valve slides 17, cooperating with a front cover or shutter plate 18 attached to the housing 11, in the manner well known in the art. Extending from the housing 11 is a key board 20 having a wall 21 extending at an angle to the 10 housing adjacent the wall 13 thereof. Fixed to the wall 21 are a pair of headed screws or rivets 22, and a second pair of headed screws or rivets 23 parallel to the first pair and vertically aligned with respect thereto. A headed screw or rivet 24 15 is fixed to the plate 21 substantially midway between the screws or rivets 22 and 23. Slidably mounted on the screws or rivets 22, 23 and 24 is an actuating member 25, comprising a vertical member 26 projecting through a slot 26' in the 20 edge of the keyboard and beyond the plate 21 and adapted to be engaged by the palm of the player's hand while pressing the keys on the keyboard. Extending from the member 26 are a plurality of 25 parallel horizontal slotted arms 28, 29 and 30 slidably receiving the shanks of the screws or rivets 22, 23, and 24 respectively.

It will now be understood that the member 25 slidably moves or reciprocates inwardly and outwardly, being guided by the screws 22, 23, and 24. 30 Fixed to the plate 21 is a rivet or pivot pin 31 disposed substantially midway between the slotted arms 28 and 30. There is also fixed to the plate 21 a rivet or pivot pin 32 located substantially midway between the slotted arms 29 and 30 and 35 vertically aligned with respect to the pin 31. Pivoted on the pin 31 is a lever 34 having a slot 35 at its upper end engaging a headed pin 36 on the slotted arm 28. At the lower end of lever 34 is a headed pin 37. Pivoted on the pin 32 is a 40 lever 38 having a slot 39 at the upper end thereof engaging the headed rivet 37. The lower end of the lever 38 is also slotted as at 40 to receive a pin 41 on the slotted arm 29. A coil tension spring 42 having one end thereof fixed to the plate 45 21 is attached at its other end to the lever 34 between the rivet 31 and the lower end of said lever. A similar spring 43 is likewise fixed at one end to the plate 21 and at its other end to the lever 38 above the pivot 32.

It will now be understood that when the member 25 is pressed inwardly, the lever 34 will be caused to rotate about the pivot 31 in a counter clockwise direction, and the lever 38 will be caused to rotate about the pivot 32 in a clockwise direc- 55

tion. When pressure is released from the member 25, the springs 42 and 43 rotate the levers 34 in opposite directions to slidably move the member 25 outwardly to normal position, as shown in Fig. 2 of the drawings.

There is also fixed to the plate 21 a pin 45 on which is rotatably mounted a wheel 46 having two diametrically opposite segmental gear portions 47. There is also fixed to one face of the wheel 46 a plurality of equiangularly spaced pins 50, there being shown in the drawings for the purpose of illustration, six such pins. Pivoted to the forward end of the central slotted arm 30 is a pawl 51 having a notch 52 at the outer end thereof for engaging the pins 50. A spring pressed arm 54 contacting the pawl 51 serves to press the latter into contact with the pins 50. It will now be understood that as the member 25 reciprocates inwardly and outwardly, the pawl 51 will rotate the wheel 46 step by step due to engagement thereof with the successive pins 50. A spring pressed pawl 55 pivoted to the plate 21 and engaging the pins 50 serves to prevent movement of the wheel in an opposite direction.

Rotatably mounted on a plate 21 are a plurality of small gears 60, each having a pair of diametrically opposed segmental gear portions 61 with notches 62 between said gear portions. As shown in the drawings, three such gears 60 are provided, although the number may be changed, if desired. The three gears are preferably spaced apart 60 degrees and are at equal radial distances from the axis of wheel 46. The gear teeth of the segmental portion 61 are adapted to mesh with the gear teeth of the segmental portions 47 of the wheel 46. Each segment 47 is adapted to rotate each wheel 60 180 degrees. There is provided for each gear 60, a pivoted member 64, spring pressed and having an end portion adapted to be received in one of the notches 62 to maintain said gear against retrograde rotation after said gear has been rotated by wheel 46.

It will now be understood that as the member 25 is reciprocated, the wheel 46 is rotated 60 degrees every time the member 25 is pressed, and the gears 60 will be rotated successively, each for 180 degrees. In other words, beginning with the parts as shown in Fig. 2, pressure of the member 25 will cause the top gear 60 to be rotated one-half revolution. Upon release of the member 25, said member will move back to its normal position. Should said member be again depressed, the segmental gear portion which has rotated the top gear 60, will be in position for rotating the second gear 60. Upon again actuating the member 25, the same segmental gear 47 will actuate the bottom gear 60. On the next actuation of the member 25, the other segmental gear 47 will rotate the top gear 60 another one-half revolution. The gears 60 are thus rotated successively each for one-half revolution, and while one of said gears is being rotated, the other two gears are held stationary by the pivoted pawls 64.

Pivoted to the plate 21 are three slotted levers 68 connected by links 69 to eccentric pins 70 on the respective gears 60. Thus, as one of the gears rotates one-half revolution, its lever 68 will be rotated in one direction, and upon rotating the same gear another 180 degrees, its lever will be rotated in an opposite direction. Such action is due to the crank action of the link 69 engaging the eccentric pin 70. Pivoted to the wall 13 of the housing 11 are three cranks 72, each being connected by an arm 73 to one of the slotted arms 68. As the slotted levers 68 are rotated, their

respective cranks will also be rotated. The cranks 72 project into the housing 11 and have fixed arms 74.

Rotatably mounted within the housing 11 on bearings 76 fixed to the top wall 14 of the housing 5 are shafts 77, there being three such shafts illustrated in the drawings. Each shaft 77 has a radial arm 78 connected by a link 79 to one of the crank arms 74. Rotation of the crank arm 72 will thus cause respective rotation of the shafts 10 77 about the axes of the latter. The shafts 77 have one or more radial arms 80 engaging one or more of the slide valves 17. The slide valves may be connected for actuation to the shaft 77 in any desired combination. As shown in the drawings, 15 one of the shafts 77 is attached to one slide valve, whereas the other two shafts are each connected to two other slide valves. In this manner, any of the slide valves may be controlled.

It will now be understood that as the member 20 25 is depressed, the shafts 77 will be successively rotated for actuating the slide valve. By actuating the member 25, any suitable relative position of the slide valve may be reached.

Means is provided for indicating the various 25 positions of the slide valves. To this end, there is fixed to the plate 21 a pivot 82. Pivoted thereon is a lever 83 having a slotted end 84 engaging a pin 85 at the forward end of the slotted arm 28. There is also pivoted to the plate 21 a pin 90 on 30 which is rotatably mounted a lever 91, one end of which is connected by a link 92 to the lower end of lever 83. The upper end of the lever 91 is slotted as at 94, and engages one end of a lever 95 pivoted as at 96 to a plate or portion 97 located 35 adjacent the top end of the keyboard. Pivoted on a plate 97 is a ratchet wheel 98 having a plurality of equiangularly spaced pins 99 and a similar number of ratchet teeth 100. Pivoted to the lever 95 is a pawl 102 held by a spring 103 in 40 engagement with the teeth 99.

It will now be understood that each time the member 25 is actuated, the motion will be transmitted through the levers 83, 84, and 95 to the pawl 102 for rotating the wheel 98. A spring 45 pressed pawl 104 engaging the ratchet teeth 100 serves to prevent retrograde movement of the ratchet wheel 98. Said ratchet wheel has a dial face 105 with numbers 106. The position of the dial may be seen through an opening 107 in the 50 plate 97. One of the numbers of the dial may be seen through said opening in all positions of the dial.

In Fig. 9, there is shown a wheel 46a having three segmental gear portions 47a. Such a wheel 55 would be employed where only two gears 60 are used instead of three, for actuating two shafts 77 instead of three.

It will thus be seen that there is provided a device in which the several objects of this invention are achieved, and which is well adapted to meet the conditions of practical use.

As various possible embodiments might be made of the above invention, and as various changes might be made in the embodiments above 65 set forth, it is to be understood that all matter herein set forth or shown in the accompanying drawings is to be interpreted as illustrative and not in a limiting sense.

Having thus described my invention, I claim 70 as new and desire to secure by Letters Patent:

1. In an accordion, a keyboard, a member adjacent one edge of the keyboard, and being slideable with respect thereto, a wheel pivoted to the keyboard and having a plurality of segmental 75

5 gear portions, means operatively connected to said member for intermittently rotating said wheel, a plurality of gears on said keyboard adapted to be successively rotated by said segmental gear portions 180 degrees upon rotation of said wheel, and means operatively connected to said gears for controlling the shutter slide valves of the accordion.

10 2. In an accordion, a keyboard, a member adjacent one edge of the keyboard, and being slideable with respect thereto, a wheel pivoted to the keyboard and having a plurality of segmental gear portions, means operatively connected to said member for intermittently rotating said wheel, a plurality of gears on said keyboard adapted to be successively rotated by said segmental gear portions 180 degrees upon rotation of said wheel, means operatively connected to said gears for controlling the shutter slide valves 15 of the accordion, and means operatively interconnected to said member for indicating the position of the slide valve.

20 3. In an accordion, a keyboard, a wheel rotatable thereon, having a plurality of segmental gear portions, means for intermittently rotating said wheel, a plurality of gears rotatably mounted on said keyboard and adapted to be successively rotated by said wheel, and means operatively connected to said gear wheels for controlling the slide valve of said shutter.

25 4. In an accordion, a keyboard, a member disposed adjacent the edge of said keyboard and slidably mounted thereon, said member being adapted to be pressed by the palm of the player's hand while pressing the keys of the keyboard, spring means for returning said member to normal position upon releasing pressure therefrom, a dial rotatably mounted on said accordion, means for actuating said dial connected to said member, a wheel rotatably mounted on said keyboard and having a plurality of pins thereon, a pawl on said member engaging said pins, said wheel having a pair of diametrically opposite segmental gear portions, a plurality of gears on said keyboard, spaced 60 degrees apart and at equal radial distances from the center of the disc, and each having a pair of opposite segmental gear portions with notches therebetween, pivoted members adapted to engage within said notches, the segmental gear portions of said wheel being adapted to rotate said gears successively each for one half revolution, levers interconnected by links to said gears, cranks pivoted to said accordion and interconnected to said levers and means on said cranks for controlling the slide shutter valves of said accordion.

30 5. In an accordion, a keyboard, a member disposed adjacent the edge of said keyboard and slidably mounted thereon, said member being adapted to be pressed by the palm of the player's hand while pressing the keys of the keyboard, spring means for returning said member to normal position upon releasing pressure therefrom, a dial rotatably mounted on said accordion, means for actuating said dial connected to said member, a wheel rotatably mounted on said keyboard and having a plurality of pins thereon, a pawl on said member engaging said pins, said wheel having a pair of diametrically opposite segmental gear portions, a plurality of gears on said keyboard, spaced 60 degrees apart and at equal radial distances from the center of the disc, and each having a pair of opposite segmental gear portions with notches therebetween, pivoted

35 members adapted to engage within said notches, the segmental gear portions of said wheel being adapted to rotate said gears successively each for one half revolution, levers interconnected by links to said gears, cranks pivoted to said accordion and interconnected to said levers and means on said cranks for controlling the slide shutter valves of said accordion, said last means including shafts rotatably mounted in said accordion and having arms engaging said slide valves and being connected to said cranks.

40 6. In an accordion, a housing for the wind cells, a shutter cover plate on said housing, a plurality of slide valves cooperating with said shutter plate, a keyboard extending from said housing, an elongated member slidably mounted on said keyboard and disposed adjacent the edge thereof and adapted to be pressed by the palm of the player's hand while pressing the keys of the keyboard, a plurality of slotted arms extending from said member, pins on said keyboard extending within said slots, a pair of levers pivoted to said keyboard connected by pin and slot connections at adjacent ends, said levers being connected to said member by pin and slot connections, springs interconnecting said levers to said keyboard, a wheel rotatably mounted on said keyboard and having gear teeth thereon, cooperating means on said member and wheel for intermittently rotating the latter through predetermined angles upon reciprocating said member, a plurality of gears on said keyboard adapted to be successively rotated through predetermined angles as said wheel is rotated, eccentric pins on said gears, levers pivoted to said keyboard and connected to said eccentric pins, cranks rotatably mounted on a wall of said housing and engaging said last mentioned levers, and a plurality of shafts rotatably mounted within said housing and connected to said cranks and valves.

45 7. In an accordion, a housing for the wind cells, a shutter cover plate on said housing, a plurality of slide valves cooperating with said shutter plate, a keyboard extending from said housing, an elongated member slidably mounted on said keyboard and disposed adjacent the edge thereof and adapted to be pressed by the palm of the player's hand while pressing the keys of the keyboard, a plurality of slotted arms extending from said member, pins on said keyboard extending within said slots, a pair of levers pivoted to said keyboard connected by pin and slot connections at adjacent ends, said levers being connected to said member by pin and slot connections, springs interconnecting said levers to said keyboard, a wheel rotatably mounted on said keyboard and having gear teeth thereon, cooperating means on said member and wheel for intermittently rotating the latter through predetermined angles upon reciprocating said member, a plurality of gears on said keyboard adapted to be successively rotated through predetermined angles as said wheel is rotated, eccentric pins on said gears, levers pivoted to said keyboard and connected to said eccentric pins, cranks rotatably mounted on a wall of said housing and engaging said last mentioned levers, a plurality of shafts rotatably mounted within said housing and connected to said cranks and valves, and a dial rotatably mounted on said accordion, means for intermittently rotating said dial, including a lever pivoted to said keyboard and having a pin and slot connection with one of the slotted arms of said member.
